METALWORKING MACHINE

Arthur J. Barrie and Raymond J. Dwyer, Toledo,
Ohio, assignors to Acorn Designing Co., Toledo,
Ohio, a corporation of Ohio

Application March 28, 1945, Serial No. 585,224

15 Claims. (Cl. 153—73)

1

This invention relates to metal working machines and more especially to machines for impressing configurations in sheet metal and involves improvements upon the machine disclosed in and forming the subject matter of our co-pending application of Serial No. 554,259, filed September 15, 1944, now U. S. Patent No. 2,421,450.

The invention embraces the provision of mechanism for impressing grooves or annular recesses into the walls of cylindrical tubing or pipe fabricated of sheet metal.

The invention comprehends a machine especially adapted for rolling or impressing grooves in the exterior walls of muffler shells and is inclusive of means for supporting the shells during working operations so as to accommodate tubular members pre-assembled within and extending longitudinally of the shells.

An object of the invention resides in the provision of improved means for stripping a muffler shell from the supporting means after the completion of the grooving operation.

Another object is the provision of retractable work supporting means for a grooving machine particularly usable for performing operations upon muffler shells whereby ample clearance space is provided for inserting the work pieces or shells in the machine and removing same therefrom.

Still another object is the provision of a work positioning abutment means resiliently or flexibly supported so as to compensate for inaccuracies in the length of work shells and to accommodate shells in which the ends are rough or are not accurately cut to lie in planes perpendicular to the longitudinal axes of the shells.

Other objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a front elevational view of a grooving machine embodying the invention;

Figure 2 is an elevational view of a portion of the mechanism illustrating our invention, certain parts being shown in section;

Figure 3 is an end elevational view of the machine shown in Figure 1;

2

Figure 4 is an end view of the structure illustrated in Figure 2, and

Figure 5 is a sectional view illustrating the work support in retracted position, and

5 Figure 6 is an end view showing circuit controlling means for actuating mechanisms forming part of the machine.

Figure 7 is an enlarged fragmentary sectional view of a portion of the construction illustrated in Figure 2.

While we have illustrated an embodiment of our invention as incorporated in a machine for rolling or impressing circumferential depressions or grooves in a thin walled cylindrical member as, for example, a muffler shell, it is to be understood that the arrangement of our invention may be used in connection with other mechanisms wherever it may be found to have utility. As illustrated, the machine is of the character

15 forming the subject matter of our co-pending application above referred to, and is inclusive of means for preliminarily supporting the shell or other work, means for supporting the shell during work performing operations, groove impressing means, work discharging means and other cooperating mechanisms. The grooving machine will be described herein in such detail only as to show the incorporation operation and utility of our present invention therewith.

20 Referring to the drawings in detail the machine is inclusive of a frame or bed 10 having adjacent each end an upwardly extending boss 11, and a horizontal longitudinally extending machined surface 12 disposed at a lower level 25 in front of bosses 11. Mounted upon the surface 12 and arranged adjacent each end portion of the machine frame is a work supporting means 30 or work supporting mechanisms 15 and 16. As these units are of substantially identical construction, a detailed description of one of said units will suffice. The bed portion of the frame 10 adjacent the machined surface 12 is formed with a longitudinally extending T-shaped slot 35 17 in which are disposed headed bolts 18 which

40 are adapted to receive nuts 19 for clamping the work supporting units 15 and 16 to the machine frame. The lower surface of the unit resting upon the surface 12 is formed with a longitudinal keyway 45 to accommodate a key 21, said key extending into the throat portion of the T-shaped slot 17, thus providing a means for maintaining the units in proper alignment on the frame 10.

50 Each of the units is arranged for longitudinal adjustment so as to accommodate work pieces 55 of different lengths. To this end, pairs of

brackets 23 and 24 are secured to each end portion of the machine frame and are bored to receive a shaft 25 having a squared end portion 26, the latter adapted to accommodate a suitable operating crank 28. Pinned or otherwise secured to each of the shafts 25 and arranged at either side of the brackets 23 are collars 27, so that during rotation of the shaft 25, the same will remain in a relatively fixed position. Secured to the side of the base or platen 29 of each unit is a laterally extending member 30 having a boss portion 31 bored and internally threaded to receive the threaded exterior portion 32 of shaft 25. Thus by releasing the nuts 19, the shafts 25 may be rotated by means of a crank to selectively adjust the units with respect to the machine frame for different lengths of work pieces.

Mounted upon the platen 29 is a member 34 which is keyed to the platen 29 by means of transversely extending keys 40 providing for lateral adjustment of the work supporting unit. The member 34 is formed with upwardly extending spaced lugs or projections 41 and 42, and disposed between the projections is a housing or bracket 43 which supports and encloses the mechanism of each work supporting unit. The housing 43 and the projections 41 and 42 are provided with aligned bores or openings to receive stub shafts or pintles 44 which are held in place by means of set screws 45. The housing 43 is formed with a rearwardly extending portion 47 which is provided with circular recesses 48 to receive coil springs 49. The portion 47 of the housing is provided with threaded openings adapted to receive threaded studs 50 which extend upwardly and centrally through the coil springs 49 and are adapted to receive a washer 51 and nuts 52 as shown in Figure 4. The tension of the springs 49 may be varied by adjusting the nuts 52. It should be noted that the work supporting unit is capable of pivotal movement about the axes of stub shafts 44, resisted only by the springs 49. By this arrangement, damage to the machine in the event that the grooving means does not cooperate properly with the work is prevented as excessive pressure will compress the springs 49 and permit pivotal movement of the housing away from the grooving die.

Each of the housings 43 of the units is formed with a hollow interior in which is disposed plain bearings or bushings 55 in which is slidably mounted a cylindrical sleeve 56. The sleeve 56 is prevented from rotating by means of a key 57 mounted in a recess formed in the interior wall of one of the bearings 55 and projects into a keyway or slot 58 as shown in Figure 2. The interior end portions of the sleeve 56 are recessed to accommodate the outer races of ball bearings 59 and 60. Mounted centrally of the bearings 59 and 60 is a shaft 63, the inner races of the ball bearings being suitably spaced by means of a sleeve 64. The one end of the shaft 63 is formed with a head 65 which forms an abutment for positioning the ball bearing 60, the other end of the shaft being provided with a threaded tenon 66 which receives securing nuts 67 adapted to retain the bearings 59 and 60 in fixed relation upon shaft 63.

Secured upon the rear end of each of the members 43 by means of bolts 68 is a sleeve 69. Mounted upon the projecting end of sleeve 69 is a plate 70 to which is secured a fitting 71 which supports a cylinder 72 in which is slidably mounted a piston 73, the piston and cylinder forming an hy-

draulic actuator for effecting longitudinal movement of the work supporting mandrel to be hereinafter described. The hydraulic connections are made by means of flexible tubes 74 and 75 connected respectively to the ends of the cylinder 72. The piston 73 is connected to piston rod 77, the latter having a threaded end extending into a plate 78, the rod 77 being locked in adjusted position by means of a nut 79. The plate 78 is secured to the end of the longitudinally slidable sleeve 56 by means of screws 80. The piston rod 77 passes through a stuffing gland 81 contained within the fitting or member 71.

The end of shaft 63 is formed to carry the muffler shell or work supporting and positioning means forming part of our invention. Mounted upon shaft 63 is a work supporting member or mandrel 84 which is secured to the shaft by means of a screw 85. The member 84 is connected to rotate with shaft 63 by means of a pin 86, the member 84 being centered upon shaft 63 by means of an annular projection 87 engaging over a cylindrical tenon 88 formed on the end of shaft 63. The member 84 is recessed as at 90 to accommodate a projecting tube 91 which forms a part of the interior structure of a muffler 92. The exterior periphery of the mandrel 84 is formed with an annular groove or recess 94 to accommodate the formation of a depression or groove 95 in the muffler shell 92. The means for positioning the shell in work performing position and for compensating for irregularities of the end edges of the muffler shell will be herein-after described.

The means for impressing the circumferential grooves in the shell is mounted upon a pair of supports or brackets 100, which are secured upon the surface 11 of the machine frame by means of bolts 101. Journaled in suitable bearings carried in boss portions 102 integrally formed with brackets 100 is a longitudinally extending shaft or arbor 103. The right hand end of shaft 103 as viewed in Figure 1 supports an arm 105 which is secured to the shaft by means of a key 106 and a set screw 107. The arm 105 is bored at its extremity to receive a pin or pintle 108, a yoke 109 straddling the arm 105 being connected to the arm by means of pin 108. The yoke 109 is adjustably connected to a rod 110 which projects into a cylinder 112 and is connected to a piston 113 slidably within the cylinder. The lower end of the cylinder is formed with a projection 115 which is pivotally connected by means of a pin 116 to a bracket 117, the latter secured to the lower rear wall of the machine frame by means of screws 118.

Mounted upon shaft 103 is a pair of similarly shaped spaced sectors or members 120. The shaft 103 is formed with a flattened surface 121, and each sector 120 is provided with a rectangularly shaped key 122 which cooperates with screws 123 for clamping the sectors 120 in adjusted position on shaft 103. The arcuate surface 124 of each sector is adapted to receive and support a segmental curved block or die 125 formed with a ridge or bead 126 which is adapted to be brought into rolling engagement with the periphery of the muffler shell 92 in order to impress a portion of the shell into the groove 94 in the work support 84 and hence to form the inwardly extending ridge or bead 95 in the shell. The sectors 120 and the grooving dies carried thereby are actuated by means of fluid under pressure conveyed to the cylinder 112 and acting upon the piston 113.

The work supporting mandrel 84 is formed with a cylindrical surface 129 which is surrounded by an annular member 130 which is formed with a plurality of regularly spaced radially extending projections or lugs 131. Disposed rearwardly thereof is a member 132 of annular configuration also having a plurality of radially extending projections 133 which are arranged for coincidence with projections 131 on member 130. The members 130 and 132 are secured together by means of screws 134. As illustrated in Figure 7, the members 130 and 132 are normally separated by a space 135, the head portions of screws 134 serving to limit the separation of said members. The registering projections 131 and 133 are formed with cylindrical recesses 136 and 137, each pair of recesses being adapted to receive and enclose a coil spring 138. As indicated in Figure 4 there are nine pairs of projections, each set recessed to receive a spring. We have found that it is desirable to employ three sets of springs, each set of different expansive force. The purpose of the employment of sets of springs of this character is to provide a means whereby the muffler shell, in engaging and abutting the member 130, will equalize and centrally position the muffler shell through the use of sets of springs 138. This is essential in order that the grooves to be formed in the muffler shell be arranged a substantially equal distance from each end of the shell, the springs 138 functioning to enhance the equalization so that each of the grooves to be formed in the shell will be equidistant from each end of the shell.

The projecting portion 81 of work support 84 is exteriorly threaded as at 141 to accommodate a threaded collar 139 which carries an annular member 140, the latter forming an abutment or limiting means for positioning member 132. By rotating members 139 and 140 through the use of a spinner wrench, an axial adjustment may be obtained of members 130 and 132 so as to provide a simple, yet effective means for controlling the distance from each end of the muffler to the groove 95 therein.

Surrounding members 130 and 132 is a cylindrically shaped sleeve or work stripping ring 142 having an exterior annular ridge 143 which is contained within recesses formed in the interior surfaces of retaining members 144 and 145 which surround sleeve 142. Retaining member 145 is secured to the housing 43 by means of screws 146, and retaining member 144 is secured to member 145 by means of screws 147. As will be seen from Figure 4, the member 144 is formed with slots 148 to accommodate the screws 147 so as to provide a means for quickly and easily disconnecting member 144 from member 145. This is accomplished by slightly releasing screws 147 and rotating member 144 in a counterclockwise direction as viewed in Figure 4 until the enlarged ends of slots 148 register with screws 147 after which member 144 may be bodily removed from the machine.

The member 142 is formed with integral inwardly extending spaced projections 150 which inter-engage or dovetail with the radial projections 131 and 133 formed respectively on members 130 and 132 as shown in Figure 4. By this means the projections 131 and 133 are in driving engagement with the annulus 142, but members 130 and 132 may move axially into nesting relation with the member 142 so that the front surface 149 thereof functions as an abutment to strip the grooved muffler shell from the work

supporting mandrel after completion of the grooving operation.

The inner surface 153 of member 131 is arcuately shaped or of convex configuration as shown in Figure 7, which convex surface is in juxtaposition to the surface 129. By the provision of this configuration formed on the abutment ring or member 131, the end of the muffler shell may be slightly irregular and under such condition the abutment 131 may tilt slightly with respect to a plane at right angles to the axis of the work supporting mandrel so as to compensate for any such irregularity in the end edge of a muffler shell. The arcuate surface 153 eliminates the tendency of binding occurring between surfaces 129 and 153.

The end of the shaft 103 opposite the arm 105 is provided with a cam ring 155 equipped with switch operating blocks or cams 156 and 157 which cooperate with switch arms 158 and 159 connected to switches 160 and 161 which are secured to the adjacent bracket 100. The switches 160 and 161 are intercalated in electric circuits (not shown) which control the operation of hydraulic valves (not shown) for controlling and directing fluid flow under pressure to and from the work supporting unit cylinders 72 and the groover actuating cylinder 112. As the electrical and hydraulic circuits per se form no part of the present invention and as they are disclosed in our co-pending application hereinbefore referred to, it is believed unnecessary to make further description of them herein.

Means are provided for preliminarily supporting the work piece or shell prior to the movement of the work supporting arbors 84 into work supporting positions. This means is inclusive of a pair of arms or levers 180 each pivoted to one of the work supporting units by means of a bolt or pivot shaft 181. The short arm of each of the levers is pivotally connected as at 162 with a link 163, the lower end of each of the links being connected to a movable armature or core 164 which is activated by a solenoid 165, the circuit of which is intercalated with one of the switches arranged at the end of the shaft 103.

The operation and arrangement of the machine is substantially as follows:

As shown in Figure 1, a fluid reservoir 170 is housed within the machine frame 10, and adjacent the reservoir is an hydraulic pump which is energized by a motor 171 which is brought into operation by closing a suitable switch (not shown) to drive the pump and set up hydraulic pressure for hydraulically actuating the several mechanisms hereinbefore described. Initially, the solenoids 165 are energized so as to maintain the levers or arms 180 in their uppermost positions as shown in Figure 4 and upon which a muffler shell or work piece is positioned by the machine operator. It is to be understood that when a muffler shell is mounted upon the levers 180, the work supporting means or mandrels 84 are in retracted position as shown in Figure 5, so as to provide at the ends of the muffler, ample space for the machine operator to manually fix or position the projecting tube portion 91 forming a part of a muffler assembly so that the tube is in a position to project same into the recess 90 formed in the work supporting mandrel 84. The tube 91 forms an element of a pre-assembly that must be inserted into the shell before the grooving operation is made. After the muffler shell 92 and the sub-assembly contained therein are in proper position, the

operator manipulates a switch (not shown) which actuates valve means to direct flow of fluid under pressure from the reservoir to the outer ends of cylinders 72 through the tubes 74. The fluid acting upon the pistons 73 drives each rod 77, shafts 63, and sleeves 56 to move the work supporting mandrels 84 into the ends of the muffler shell 92 to the position shown in Figure 1. The members 131 and 133 are carried forward with work support 84 until the abutment member 131 engages the end edge of the muffler shell. In the event that member 131 on one work supporting unit engages the muffler shell in advance of the other abutment member, the springs 138 will equalize the position of the muffler shell so that the distance from the muffler end edge to the point of application of the grooving die will be substantially equi-distant from each end of the shell. Should the end edge of the muffler shell or work piece be rough or irregular, the abutments 131 may tilt by reason of the arcuate surface 153 to accommodate and compensate for such irregularities. When each work supporting mandrel 84 reaches its work supporting position as shown in Figure 3, the fluid pressure in cylinders 72 attains a predetermined value and is caused to actuate a mercoind switch (not shown) which completes a circuit to the solenoid of a valve means for establishing a fluid flow under pressure to the upper end of the cylinder 112. The circuit to the solenoids 165 is interrupted so that the arms 180 swing downwardly about the axes of shafts 181 under the influence of gravity. Fluid pressure moves the piston 113 downwardly in cylinder 112 and through the rod 110 and yoke 109, causes rotation of shaft 103 and the grooving elements 124. The movement of the elements 124 brings the faces of die blocks 125 and the beads 126 into rolling engagement with the muffler shell 92. As the beads 126 are in planes aligned with the grooves 94 formed in the work supporting mandrels 84, a pair of circumferential grooves 95 are impressed in the muffler shell 92. When the members 124 have completed grooving operation, the switch 161 is actuated by the block 156 to energize means (not shown) for diverting flow of fluid to the lower end of cylinder 112 to drive pistons 113 upwardly and return the groovers 124 to their initial position. The switch means adjacent the end of shaft 103 cooperates with a cam carried by the shaft and actuate valve means to direct fluid flow through the tubes 75 to the inner ends of the cylinders 72. The pistons 73 are thus reciprocated in the opposite direction and through the medium of shaft 65, sleeve 56 and associated elements, the work supporting mandrel 84 is retracted to the position illustrated in Figure 5. During retractive movement of the mandrel 84, the members 130 and 132 are moved with the mandrel 84 and the projections thereon slide into the recesses formed by the projections 150 on the member 142. The muffler may be stripped off of the mandrels 84 without engaging the front surface 149 of member 142. Should one end of the muffler shell move with one of the mandrels 84, it will be stripped when the end edge of the shell abuts or engages surface 149 during retractive movement of the mandrel.

At the completion of a grooving operation, switching means energize solenoids 165 to elevate the arms 180 to work supporting position. When the work supporting mandrels 84 are completely retracted, and the grooved shell is supported upon the arms 180, switching means then operate to de-energize the solenoids, permitting the

arms 180 to fall or swing downwardly and direct the shell on to the ramp 175 formed at the rear of the machine for discharging the grooved shells.

It is apparent that, within the scope of the invention, modifications and different arrangements may be made other than is herein disclosed, and the present disclosure is illustrative merely, the invention comprehending all variations thereof.

10. What we claim is:

1. In combination, a frame; a work supporting mandrel mounted upon said support; an annular member surrounding said mandrel and adapted to engage and position the work upon the mandrel; a stripper ring surrounding said annular member; said annular member and stripper ring being formed with interengaging projections whereby the annular member is adapted for slidable movement within said stripper ring upon longitudinal movement of said mandrel; said stripper ring being arranged to engage and strip the work from the mandrel during retractive movement of said mandrel.

2. In combination, a frame; a work piece supporting mandrel mounted upon said support; an annular member carried by said mandrel and adapted to position the work piece; a stripper ring mounted upon said housing; said annular member and stripper ring having interengaging projections whereby said stripper ring is rotatable with said annular member; said mandrel and annular member being arranged for slidable movement relative to said stripper ring whereby the latter engages and strips the work piece from the mandrel.

3. In combination, a support; a work piece supporting mandrel mounted upon said support; an annular member carried by said mandrel and adapted to position the work piece; a stripper ring journaled for rotary movement upon said housing; said annular member and stripper ring having interlocking portions; said mandrel and annular member being arranged for slidable movement relative to said stripper ring whereby the latter engages and strips the work piece from the mandrel.

4. In combination, a support; a work piece supporting mandrel mounted upon said support; an annular member carried by said mandrel and adapted to position the work piece; a relatively stationary stripper ring mounted upon said housing and surrounding said annular member; said annular member and stripper ring having interengaging portions; said mandrel and annular member being arranged for slidable movement relative to said stripper ring whereby the latter engages and strips the work piece from the mandrel.

5. In combination, a support; a work piece supporting mandrel mounted for slidable and rotational movement upon said support; a work piece positioning ring mounted upon said mandrel; a stripper ring mounted upon said support; said rings having interengaging splines formed thereon; said mandrel and positioning ring arranged to be retracted within the stripper ring whereby the work piece is caused to engage the stripper ring to remove the work piece from said mandrel.

6. In combination, means for impressing grooves in the walls of muffler shells including a frame; a housing supported upon the frame; a shell supporting mandrel associated with said housing for rotary and longitudinal movement with respect thereto; a shell positioning abut-

ment associated with said mandrel; a stripper ring carried by said housing; means including a projection formed upon said abutment and in interengaging relation with said stripper ring whereby the latter is adapted for rotative movement with said shell positioning abutment, and means for retracting said mandrel whereby said stripper ring engages and removes the shell from the mandrel.

7. In combination, means for impressing grooves in the walls of muffler shells including a frame; a housing supported upon the frame; a shell supporting mandrel associated with said housing for rotary and longitudinal movement with respect thereto; a shell positioning ring carried by said mandrel; a stripper ring carried by said housing; means including a plurality of projections formed upon each of said rings and in interengaging relation whereby said stripper ring is adapted for rotative movement with said shell positioning ring, and means for retracting said mandrel whereby said stripper ring engages and removes the shell from the mandrel.

8. In combination, means for impressing a groove in a thin walled member including a frame; a pair of spaced housings supported upon said frame; a mandrel adapted to support the thin walled member movably mounted upon each of said housings; a grooving means adapted to engage and impress a groove in the thin walled member; an annular member mounted upon said mandrel and movable therewith for positioning the thin walled member; said annular member having a plurality of radially arranged projections formed thereon; a second annular member associated with said housing formed with projections engageable with the projections on said first annular member; said mandrel and first annular member being arranged for longitudinal movement relative to the said second annular member whereby the thin walled member in engagement with said mandrel is stripped therefrom upon longitudinal movement of said mandrel.

9. In combination, means for impressing a groove in a thin walled member including a frame; a housing supported upon said frame; a mandrel adapted to support the thin walled member movably mounted upon said housing; grooving means adapted to engage and impress a groove in the thin walled member; an annular member mounted upon said mandrel and movable therewith for positioning the thin walled member; said annular member having a plurality of radially arranged projections formed thereon; a second annular member associated with said housing formed with projections engageable with the projections on said first annular member; said mandrel and first annular member being arranged for longitudinal movement relative to the said second annular member whereby the thin walled member engages said second annular member and is disengaged from said mandrel.

10. In combination, means for impressing grooves in the walls of muffler shells including a frame; a pair of housings supported upon said frame; a mandrel mounted in each of said housings and arranged for longitudinal and rotational movement relative thereto; said mandrels adapted to support a muffler shell; a grooving means mounted upon said frame and movable into engagement with a muffler shell for forming annular grooves therein; a pair of rings surrounding each of said mandrels; resilient means

interposed between said rings; a stripper member surrounding said rings; said rings and stripper member being formed with interengaging projections whereby said stripper member is rotatable with said rings; one of said rings of each pair being arranged for relative slidable movement axially of its adjacent mandrel for positioning a muffler shell.

11. In combination, means for impressing grooves in the walls of muffler shells including a frame; a housing supported upon said frame; a mandrel mounted in said housing and arranged for longitudinal and rotational movement relative thereto; said mandrel adapted to support a muffler shell, a grooving means mounted upon said frame and movable into engagement with a muffler shell for forming annular grooves therein; a pair of rings mounted upon and surrounding said mandrel and adapted to position a shell upon the mandrel; resilient means interposed between said rings; a stripper member surrounding said rings; said rings and stripper member being formed with radially arranged projections adapted for interengagement whereby said stripper member is rotatable with said rings and said rings are relatively slidable with respect to said stripper member.

12. In combination, means for impressing grooves in the walls of muffler shells including a frame; a pair of housings supported upon said frame; a mandrel mounted in each of said housings and arranged for longitudinal and rotational movement relative thereto; said mandrels adapted to support a muffler shell, a grooving means mounted upon said frame and movable into a muffler shell for forming annular grooves therein; a pair of rings surrounding each of said mandrels and mounted thereon for positioning a shell on said mandrels; resilient means interposed between said rings; a stripper member surrounding said rings; said rings and stripper member being formed with radially arranged projections adapted for interengagement whereby said stripper member is rotatable with said rings and said rings are arranged for relative slidable movement axially of said stripper member.

13. In combination, means for impressing grooves in a thin walled hollow member including a frame; a housing supported upon said frame; means for supporting the hollow member during grooving operations including a mandrel mounted on said housing and relatively movable with respect thereto; a ring surrounding the mandrel and adapted for engagement with the hollow member for positioning the latter upon the mandrel; a stripper mounted upon said housing; interengaging means on said ring and stripper whereby said ring is adapted for relative slidable movement and for simultaneous rotary movement with respect to said stripper; said stripper being arranged whereby engagement of stripper with the hollow member upon retractive movement of the mandrel will disengage the member from the mandrel.

14. In combination, means for impressing grooves in a thin walled hollow member including a frame; a housing supported upon said frame; means for supporting the hollow member during grooving operations including a mandrel mounted on said housing and relatively movable with respect thereto; a ring surrounding the mandrel and adapted for engagement with the hollow member for positioning the latter upon the mandrel; said ring having a convex inner surface adjacent said mandrel; a second ring arranged

adjacent said first mentioned ring; resilient means disposed between said rings; a stripper mounted upon said housing; interengaging means on said rings and stripper whereby said rings are adapted for relative slidable movement and for simultaneous rotary movement with respect to said stripper; said stripper being arranged whereby engagement of the stripper with the hollow member upon retractive movement of the mandrel will disengage the member from the mandrel.

15. In combination, means for impressing grooves in a thin walled hollow member including a frame; a pair of spaced housings adjustably supported upon said frame; means for supporting the hollow member during grooving operations including a mandrel mounted on each of said housings and relatively movable with respect thereto; a ring surrounding the mandrel and adapted for engagement with the hollow member for positioning the latter upon the mandrel; a second ring arranged adjacent said first men-

tioned ring; resilient means disposed between said rings; a stripper mounted upon each of said housings; interengaging means on said rings and stripper whereby said rings are adapted for relative slidable movement and for simultaneous rotary movement with respect to said stripper, said stripper being arranged whereby engagement of either with the hollow member upon retractive movement of the mandrels will strip the member from the mandrel adjacent thereto.
